(57) **CLAIM**

The ornamental design for a dental prophylaxis paste container ring holder, as shown and described.

DESCRIPTION

FIG. 1 is a perspective view of the dental prophylaxis paste container ring holder shown on a person's finger (in phantom) and retaining a container of prophylaxis paste (in phantom);

FIG. 2 is an end elevational view of the ring;

FIG. 3 is an opposite end elevational view of the ring from that in FIG. 2;

FIG. 4 is a bottom view of the ring;

FIG. 5 is a top view of the ring;

FIG. 6 is an end elevational view of the ring; and,

FIG. 7 is an opposite end elevational view of the ring from that in FIG. 6.
